UNITED STATES PATENT OFFICE

2,091,089

CARBON HOLDING DEVICE

Charles L. Winter, Chicago, Ill., assignor to
United Autographic Register Co., Chicago, Ill.,
a corporation of Illinois

Application March 25, 1935, Serial No. 12,958

4 Claims. (Cl. 282—29)

This invention relates particularly to duplicating machines and improved means for separating stationery strips and supporting a transfer strip in interleaved relation with the stationery.

The primary object of the invention is to provide an improved carbon supporting bar having a rearwardly extending slitter bar which serves to protect the folded end of a transfer strip 10 anchored thereto.

The device has particular utility in connection with typewriting machines adapted to fill in forms on continuous form stationery. The device, if desired, may be mounted so as to move 15 forwardly with the stationery to writing position and may later be retracted to strip the transfer material into the next succeeding set of forms as is well understood in the art. Heretofore carbon holding blades have been provided 20 to extend from one lateral edge of the supporting device into interleaved relation with the stationery, particularly with fanfold stationery, and in some cases slitters have been provided in the member to separate the fanfold stationery 25 at its connected edge. However, the present carbon blade is supported in a novel manner so as to float between the stationery strips, that is, the blade is allowed to move slightly up or down on the supporting posts. The blade is inexpensive, easy to use, and is interchangeable 30 with other carbon supporting blades in the same device.

The invention is illustrated in the preferred embodiment illustrated in the accompanying drawing, in which,—

Fig. 1 is a broken side elevational view of a device embodying the invention; Fig. 2 is a transverse sectional view taken as indicated at line 2 of Fig. 1; Fig. 3 is a plan view of the same 40 with the stationery partly broken away; and Fig. 4 is a longitudinal section of the blade taken as indicated at line 4 of Fig. 3.

In the embodiment illustrated, A designates a base member equipped with upwardly extending 45 posts A'; B, a blade having a transverse slitter bar B' and a transverse carbon-anchor bar B².

The base member A comprises a sheet metal plate having its rear end portion curled downwardly to form a guide bar 10 over which fanfold stationery 11 may be drawn. The front portion of the plate is equipped with laterally extending arms 12 whose edge portions 13 are turned 50 downwardly to form flanges and receive a pivotally mounted bail 14. The plate is equipped

with suitable downwardly extending studs 15 which enable the device to be secured to a bracket 16 provided on the duplicating machine. The posts A' preferably are slotted as indicated at 17, to reduce the weight of the device and are secured to the base member by nuts 18. Preferably, the posts are of rectangular cross section and have a cut away portion 19 so that the bail 14 may be snapped into vertical position. The base plate is further provided at its rear end with laterally extending guide fingers 20 which are adjustably secured to the base plate by means of screws 21.

The blade B preferably is made of sheet metal such as aluminum and has laterally extending 15 ears 22 which are adapted to fit loosely over the posts A'. The slitter bar B' is integrally formed therewith and extends rearwardly between the strips of the advancing stationery. Its end portions 23 extend forwardly and outwardly towards the ears 22 and serve as slitters for the edge portions of the fanfold stationery 11. The transverse carbon-anchoring bar B² is integrally formed with the slitter bar and is adapted to receive the folded end portion 24 of the transfer strip 25 through a lateral slot 26. The slot has rearwardly extending cut out portions 27 to facilitate insertion of light spring clips 28 around the fold 24.

It will be seen that the support thus provided permits the blades B to be moved up and down slightly on the posts A' under the influence of the rearwardly extending bar B'. The blades may be inverted and their relative position in a pile is immaterial as no spacers are provided between the ears 22.

The foregoing detailed description has been given for clearness of understanding only, and no unnecessary limitations should be understood therefrom, but the appended claims should be construed as broadly as permissible, in view of the prior art.

What I regard as new, and desire to secure by Letters Patent, is:

1. A carbon-holding device for a typewriting machine comprising: a base-member over which fanfold stationery-strips may be drawn forwardly into writing position, said base member having at each lateral end portion an upwardly extending post; and a thin carbon-holding blade adapted to be interleaved with said stationery and loosely impaled by both of said posts so as to float between the stationery strips.

2. A carbon-holding device for a duplicating machine comprising: a base-member over which

fanfold stationery-strips may be drawn forwardly into writing position, said base member having at each lateral end portion an upwardly extending post; a thin carbon-holding blade adapted to be interleaved with said stationery and loosely impaled by both of said posts so as to float between the stationery strips, said blade comprising a transverse bar to which the rear ends of carbon strips may be anchored, and an integrally formed 10 parallel slitter bar whose rear edge is of less width than said strips and whose end portions extend forwardly and outwardly beyond the edge portions of the strips; and bails pivotally mounted on said base-member and adapted to snap over 15 the posts to limit the vertical movement of said blades.

3. A carbon holding member adapted to float between strips of fanfold stationery comprising: a thin blade having lateral mounting-ears and

having rear lateral end-portions tapering forwardly and outwardly towards said ears to form slitters, said blade having a transverse slot adapted to receive the rear end portion of a transfer strip. 5

4. A carbon-holding and paper slitting device adapted to float between strips of continuous-form fanfold stationery comprising: a thin blade having lateral mounting-ears and rear lateral end-portions tapering forwardly and outwardly 10 towards said ears to form slitters, said blade having a transverse slot adapted to receive the rear end portion of a transfer strip, said slot having rearwardly extending cut-out portions whereby separate carbon clips may be admitted to clamp 15 said transfer slip over the front portion of the blade.

CHARLES L. WINTER.
